UNITED STATES PATENT OFFICE.

ALFRED E. REYNOLDS, OF DANBURY, CONNECTICUT.

DESIGN FOR A CANDLESTICK.

Application filed October 2, 1923. Serial No. 7,380. Term of patent 3½ years.

To all whom it may concern:

Be it known that I, ALFRED E. REYNOLDS, a citizen of the United States, residing at Danbury, Fairfield County, Connecticut, have invented a new, original, and ornamental Design for Candlesticks, of which the following is a specification, reference being had to the accompanying drawing, forming part thereof.

The figure is a view in elevation of a candlestick, showing my new design.

I claim:

The ornamental design for a candlestick as shown.

ALFRED E. REYNOLDS.
